UNITED STATES PATENT OFFICE.

EDWARD T. WEBSTER, OF MILWAUKEE, WISCONSIN.

DESIGN FOR AN EARTHENWARE CLOSET-BOWL.

No. 37,807.

Specification for Design.

Patented Feb. 6, 1906.

Application filed November 17, 1905. Serial No. 287,902. Term of patent 14 years.

To all whom it may concern:

Be it known that I, EDWARD T. WEBSTER, a citizen of the United States, residing at Milwaukee, in the county of Milwaukee and State of Wisconsin, have invented a new, original, and ornamental Design for Earthenware Closet-Bowls, of which the following is a specification, reference being had to the accompanying drawing, forming part thereof,

which drawing represents the same in perspective.

I claim—

The ornamental design for an earthenware closet-bowl, as shown.

EDWARD T. WEBSTER.
